UNITED STATES PATENT OFFICE

154,610

DESIGN FOR A DISPLAY CASING FOR PENCIL OR THE LIKE

Paul R. Kuhn, Brentwood, Mo., assignor to Rite-point Co., St. Louis, Mo., a corporation of Missouri

Application November 1, 1947, Serial No. 142,254

Term of patent 14 years

(Cl. D74—24)

To all whom it may concern:

Be it known that I, Paul R. Kuhn, a citizen of the United States, residing at Brentwood, county of St. Louis, and State of Missouri, have invented a new, original, and ornamental Design for Display Casing for Pencil or the like, of which the following is a specification, reference being had to the accompanying drawings, forming part thereof.

Fig. 1 is a top plan view of a display casing for pencil or the like, showing my new design;

Fig. 2 is an elevational view of the same in an upright position;

Fig. 3 is an elevational view in upside down position; and

Fig. 4 is a fragmentary vertical sectional view through the upper portion of Fig. 2.

The dominant features of my invention reside in the portions shown in full lines; and include an opaque tube topped by a transparent spherical cap, within which is a central bore extending into

the tube and containing a liquid with an unsupported display body of a specific gravity differing from the liquid, whereby in one position of the pencil the display body is out of view within the tube, but in the reverse position it is displayed and magnified through the spherical cap.

I claim:

The ornamental design for a display casing for pencil or the like, substantially as shown and described.

PAUL R. KUHN.
